Primary Examiner — Philip S Hyder(74) *Attorney, Agent, or Firm* — Carter, Deluca & Farrell LLP(57) **CLAIM**

The ornamental design for a tool handle, as shown and described.

DESCRIPTION

FIG. 1 is a bottom perspective view of a tool handle in accordance with the present design;

FIG. 2 is a top perspective view thereof;

FIG. 3 is rear elevational view thereof;

FIG. 4 is a front elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines shown in the drawings illustrate portions of a tool handle that form no part of the claimed design.

1 Claim, 6 Drawing Sheets# US D992,397 S
